UNITED STATES PATENT OFFICE.

WILLIAM G. KENDALL, OF NEWARK, NEW JERSEY, ASSIGNOR OF ONE-HALF TO
KENNETH A. SHEPARD, OF EAST ORANGE, NEW JERSEY.

CURTAIN-HOOK.

1,169,650.

Specification of Letters Patent.

Patented Jan. 25, 1916.

Application filed June 6, 1914. Serial No. 843,523.

To all whom it may concern:

Be it known that I, WILLIAM G. KENDALL, citizen of the United States, residing at Newark, in the county of Essex and State 5 of New Jersey, have invented certain new and useful Improvements in Curtain-Hooks, of which the following is a specification.

My present invention relates to a new and useful form of fastening device and more 10 particularly to a fastening device for use in securing the supporting cords of sash curtains, the object of my present invention being the provision of a simple fastening device which may be readily applied to the 15 sides or facing strips of the window casing to receive the ends of either elastic or non-elastic sash curtain supporting cords and to hold such cords against sagging, without the employment of any anchoring devices, 20 such as knots in the cord, or the like.

A further object of my invention is the provision of a fastener in the form of a hook having a threaded shank portion extending at right angles to the bisector of the bight 25 portion of the hook in which the bill of the hook is offset laterally at an angle to the plane of the body of the hook and its shank and further in which the bill of the hook extends above the line of the shank. By this 30 construction, the insertion of the cord in the hook is greatly facilitated and strain exerted upon the cord tends to increase the gripping action of the hook upon the cord.

A still further object of my invention consists in constructing a hook so formed that the cord may be positioned directly between the bill and body portion of the hook and extended in any direction therefrom, the outer face of the hook bill being grooved 40 transversely to receive the cord and prevent its displacement if the cord is turned about the bill of the hook.

With these and other objects in view, my invention will be more fully described, illustrated in the accompanying drawings, and then specifically pointed out in the claim 45 which forms a part of this application.

In the drawings: Figure 1 is a perspective view of a pair of my improved hooks in 50 use as supports for a sash curtain; Fig. 2 is a side elevation of one of the hooks removed

from the window casing; Fig. 3 is a front elevation of the same hook; Fig. 4 is a top plan view of the hook.

Corresponding and like parts are referred 55 to in the following description and indicated in all the views of the drawings by the same reference characters.

The preferred embodiment of my invention comprises a fastener having a cord engaging hook and attaching shank, the entire fastener being formed from a single 60 length of relatively heavy and stiff resilient wire.

In forming the fastener, one end 10 of the 65 wire is rebent to extend back at a relatively acute angle to the remainder of the wire, whereby a V-shaped bight or hook portion is formed. The other end of the wire is bent laterally away from the hook just formed to 70 provide an attaching shank 11 extending substantially at right angles to the bisector of the bight portion of the hook and being provided with screw threads 12 throughout the greater portion of its length. As best 75 shown in Fig. 2 of the drawings, the bill 10 of the hook extends at its free end above the level of the shank 11, and as best shown in Fig. 3 of the drawings, this bill is offset or disposed angularly with respect to the 80 plane of the body portion 13 of the hook and shank 11. The upper and lower faces of the unthreaded portion of the shank 11, adjacent the body portion 13 of the hook, are flattened as shown at 14 in Fig. 4 in 85 order that the hook may be readily grasped by a pair of pliers or a wrench to assist in threading it into place. For this reason it is unnecessary to grasp the hook proper in applying the fastener and all likelihood of 90 springing the bill portion of the hook into the plane of the shank and body portion of the hook is therefore avoided.

Although, while not essential to the proper and effective working of the fasteners, I preferably construct the above fasteners in rights and lefts for use with sash curtains and other like devices in order to insure somewhat more positive engagement with the curtain cord, as will be later explained. That is, the bill portion of one hook will be directed toward the left of

the shank, while the bill portion of the other will be directed toward the right, the former being positioned at the left hand side of the window and the other at the right hand side. Also I preferably provide the intermediate portion of the bill 10 of the hook with a transversely extending groove 15 for a reason which will be hereinafter explained.

10 In order to insure a clear understanding of the method in which my fastener is employed as a support for sash curtains, I have illustrated a pair of my fasteners so used, the fasteners being threaded into the facing strips 16 at either side of the window casing 17 with the free ends of their bill portions directed toward the outer edges of such strips, that is, with the hook portion, as a whole, lying in a substantially horizontal plane.

15 The sash curtain 18 is provided at its upper edge with a hem 19 through which is run the supporting cord 20, which is preferably circular in cross section and which may be either non-elastic or elastic as preferred, the latter usually being found more efficient. The ends of the cord are protected against raveling by being bound with metal balls 21 or other like protectors. As will be 20 appreciated, one end of the cord is wedged in the bight portion of one fastener, after which the cord is drawn tight and wedged in the bight portion of the other fastener. The tendency of the cord to draw through 25 the V-shaped bight portions of the fasteners not only causes the cord to wedge more tightly in the bight portions of the fasteners, but also will tend to swing the bill portions 10 of the fasteners into the planes of their body and shank portions, this swinging of 30 the bill portions restricting the space between them and the body portions and therefore causing a still closer engagement of the cord by the fasteners. It is to secure the full 35 benefit of this feature that I prefer to construct the hooks in rights and lefts, as previously described.

40 If desired, the fasteners may be attached to the window casing in such a manner that 50 their bight portions are directed upwardly, in which case the cord is preferably secured in the fasteners in a slightly different manner, one end of the cord being passed inwardly and wedged in the bight portion of 55 the fastener at one side of the window and the cord then drawn about the bill of such fastener to rest in the groove 15 and its other end drawn across the bill of the other fastener to rest in its groove 15 and then rebent 60 or turned and wedged in the bight portion of the latter fastener. This method of securing the cord is of particular advantage in case an elastic cord is used as the elasticity of the cord, by this method, is still further 65 utilized to cause swinging of the bill por-

tions of the fasteners into the planes of their body and shank portions to insure firm clamping or gripping of the cord. Also with this particular type of hook construction, when the cord is applied in the above 70 manner, the groove 15 holds the cord against movement toward the mouth of the hook and the strain on the hook exerted by the cord swings the bill portion of the hook to additionally wedge the cord and hold it against 75 movement through the hook. This strain tending to additionally wedge the cord would, if it were not for the transverse groove, be apt to cause the cord to ride toward the throat of the hook and be released. 80 On the other hand, the mere engagement of the cord in the groove, were it not for the angular disposition of the bill portion of the hook with respect to the plane of the other portions, would have practically no effect in 85 wedging the cord in the hook.

85 It should be noted at this point that by extending the free end of the bill of the fastener or hook above the shank, as shown in Figs. 2 and 3 of the drawings, the application of the cord to the fastener is greatly facilitated as the cord may be merely drawn across the shank of the hook, stretched tightly, and then moved outwardly slightly until it sinks into the bight portion of the 95 hook.

90 It will of course be understood, that I do not wish in any way to be limited to the specific details of construction, illustrated and described, as various changes, within 100 the scope of the appended claim, may be made at any time without in the slightest degree departing from the spirit of my invention.

95 The fastening devices will, preferably, 105 either be formed of galvanized wire or the finished fastener will be galvanized, japanned, plated or otherwise coated to protect it from the elements.

100 The hooks, instead of being bent from 110 wire, may be dropforged or cast out of brass or any other suitable metal.

Having thus described the invention, what is claimed as new is:

110 A fastening device formed from resilient wire bent to provide a V-shaped hook having 115 a body portion, a bill portion and a shank portion extending at substantially right angles to the bisector of the angle of the hook between the bill and body portions, the bill 120 portion of the hook so formed, being bent laterally to extend at an acute angle to the plane of the body and shank portions of the hook and being formed in its outer face with a transverse groove adapted, when a cord is 125 wedged in the V-shaped bight portion of the hook with that stretch of the cord subject to strain, wound about the bill of the hook to receive said wound portion of the cord, whereby when the cord is under strain, the 130

groove will hold the cord against movement toward the mouth of the hook and the strain on the hook will swing the bill toward the plane of the body and shank portions of the hook to additionally wedge the cord and hold it against movement through the hook.

In testimony whereof I affix my signature in presence of two witnesses.
